UNITED STATES PATENT OFFICE.

JOHN HINES, OF BUFFALO, NEW YORK.

LINE-ANCHORING DEVICE

Application filed December 14, 1927. Serial No. 240,034.

My invention relates to a line anchoring device for clothes lines and the like, and the object of my invention is to construct a device for supporting and clamping a line to prevent the slipping thereof until released.

A further object of my invention is to construct my device of simple and comparatively inexpensive form, and comprising a hook member and a hook supporting plate member having an inverted T-shaped slot therein, such slot having the dual function of providing a means for mounting the hook upon the plate and also forming part of the means for clamping the line.

A still further object of my invention is to provide means in the line clamping portion of the hook member for preventing lateral movement of the clamped portion of the line.

My invention consists of a line anchoring device constructed and arranged all as hereinafter more particularly described and illustrated in the accompanying drawing in which:

Fig. 1 is a perspective view of my line anchoring device mounted upon a post, showing a line positioned thereon.

Fig. 2 is a front elevational view of the hook member of my device.

Fig. 3 is a vertical cross-sectional view of the device, being taken through the line 3-3 Fig. 1.

Fig. 4 is a transverse cross-sectional view showing the line clamping bar of the hook, being taken through the line 4-4 Fig. 2.

Fig. 5 is a vertical cross-sectional view of the bar illustrated in Fig. 4 taken through the line 5-5 of such figure.

Like characters of reference indicate corresponding parts in the different views.

Upon reference to the drawings, it will be readily apparent that my device consists only of two integral parts, namely the anchor hook and the supporting plate, the latter being of substantially rectangular shape and formed intermediately of its height with a transverse convex corrugation 2 which constitutes a seating for the transverse pivot bar 3 which is formed intermediately of the height of the hook member.

4 is a slot of inverted T-shape formed within the plate 1 in the vicinity of its lower end so that the upper end thereof passes through the corrugation 2.

The hook member consists of an upper

U-shaped portion 5 mounted upon a rearwardly and downwardly extending lever 6 which is furnished intermediately of its height with the bar 3 as before described. 60 The lower end of such lever is formed with a transverse line clamping bar member 7 which is of the form clearly shown in Figs. 4 and 5, wherein it is furnished upon its line contacting side 8 with an edge 9 and 65 also with a plurality of line receiving recesses 10 which are furnished with edges 11.

Upon reference to Fig. 1 of the drawings, it will be seen that the length of the lower portion of the slot 5 is greater than the 70 length of the bar member 7 so that such bar member may freely enter the slot. When my device is being assembled, the bar member 7 and bar 3 are inserted through the slot 5 from the outer face of the plate 2 75 and when the bar 4 is passed through the slot to the back of the plate, the hook member is moved upwardly to the upper portion of the slot when the pivotal bar 3 will enter the convex corrugation 2. When this 80 is done the upper portion of the hook member may be swung towards the plate into the position illustrated in Fig. 1, wherein the clamping bar is situated outside the slot 5. 85

In practice the line is positioned within the U-shaped portion of the hook member and passed downwardly between the locking bar 7 and the face of the plate 2 being pulled until the required tautness of line is attained. Upon the line being released, its pull upon the upper end of the lever will force the lower end of the lever and the locking bar 7 inwardly towards the plate, thus clamping the line between such 90 bar and the upper and lower edges 12 and 13 of the slot 5. If it is desired to support two lengths of line from the one device, a length of line is passed down each side of the hook member as illustrated in Fig. 1, the lines 100 being tightened by pulling the loop 14 which is thus formed. By the provision of the recessed portions 10 in the line clamping bar 7 which are adapted to receive the line, I have formed a simple means for preventing 105 any possibility of the line being accidentally jerked past the ends of such bar, and also by forming the edge 9 upon the bar and edges 11 in the recesses, I have provided a much better clamp than would be the case 110 if the bar 7 were formed with a smooth line contacting face.

From the foregoing description it will be readily apparent that I have constructed a line anchoring device of extremely inexpensive character and simple form wherein I have utilized the slot in the plate both as a means for permitting the hook to be readily mounted upon the plate and also to constitute a part of the line clamp as the line when clamped is held between the upper and lower edges 12 and 13 of the slot and either of the edges 9 and 10 in the bar 7.

What I claim as my invention is:

1. A line anchoring hook comprising a base plate having an inverted T-shaped slot 13 therein, a convex corrugation extending across the plate through the upper portion of the slot, a lever extending upwardly through the slotted portion of the corrugation, a U-shaped line receiving member formed on the top of the lever, a transverse bar formed intermediately of the height of the lever and adapted to be positioned behind and in alignment with the corrugation to constitute a pivotal connection between the lever and the plate, and a line gripping bar formed upon the lower end of the lever and positioned oppositely the lower portion of the inverted T-shaped slot, so that a line gripping means is constituted between said bar and the upper and lower edges of such lower portion of the slot.
2. A line anchoring hook comprising a base plate having an inverted T-shaped slot therein, a convex corrugation extending across the plate through the upper portion of the slot, a lever extending upwardly through the slotted portion of the corrugation, a U-shaped line receiving member

formed on the top of the lever, a transverse bar formed intermediately of the height of the lever and adapted to be positioned behind and in alignment with the corrugation to constitute a pivotal connection between the lever and the plate, a line gripping bar formed upon the lower end of the lever and positioned oppositely the lower portion of the inverted T-shaped slot and having an edge formed upon and extending along its line engaging face so that a line gripping means is constituted between said edge of the bar and the upper and lower edges of such lower portion of the slot.

3. A line anchoring hook comprising a base plate having an inverted T-shaped slot therein, a convex corrugation extending across the plate through the upper portion of the slot, a lever extending upwardly through the slotted portion of the corrugation, a U-shaped line receiving member formed on the top of the lever, a transverse bar formed intermediately of the height of the lever and adapted to be positioned behind and in alignment with the corrugation to constitute a pivotal connection between the lever and the plate, a line gripping bar formed upon the lower end of the lever and positioned oppositely the lower portion of the inverted T-shaped slot and having an edge formed upon and extending along its line engaging face, and in which a line receiving recess is formed so that a line gripping means is constituted between the edge in the recess and the upper and lower edges of such lower part of the slot.

JOHN HINES.
